TYPEWRITING MACHINE

Anthony Utz, Hartford, Conn., assignor to Royal Typewriter Company, Inc., New York, N. Y., a corporation of New York

Application May 2, 1935, Serial No. 19,471

15 Claims. (Cl. 197—33)

This invention relates to new and useful improvements in typewriting machines generally, although more particularly to a machine wherein the spring tensions of the type actions are 5 adjustable to vary the strengths of the springs to suit the individual operator.

Among the several objects of the invention are to provide a manually operable actuator for an adjustable anchor plate to which the springs are 10 connected, and which is located at the front of the machine, whereby the operator may view an indicator which is associated with the actuator and whereby the latter may be readily operated whenever it is desired to vary the tensions 15 of the springs.

In the drawings:—

Figure 1 is a side elevation of a typewriting machine embodying my invention, certain of the parts being shown in dotted lines.

Figure 2 is a front elevation thereof, some of the key levers being omitted for the sake of clarity.

Figure 3 is a vertical transverse sectional view taken on the line 3—3 of Figure 1, the key levers, 25 however, being omitted.

Figure 4 is a top plan view showing particularly the means for pivotally supporting the anchor plate, the front plate of the machine being shown in section.

Figure 5 is a vertical longitudinal sectional view 30 through the machine.

Figure 6 is an enlarged longitudinal sectional view through the machine showing particularly the means for supporting the anchor plate, the 35 spring connection between the plate and one of the front links, together with the actuator for adjusting the anchor plate.

Figure 7 is a detail perspective view showing a slightly different form of scale indicia than is 40 shown in Figure 2, and

Figure 8 is a front elevation of a still further modified form of scale indicia.

Referring to the accompanying drawings, I have illustrated my invention as being applied 45 to a Royal portable typewriting machine, although it will be understood that the invention may be applied equally as well to other known machines.

The general frame of this machine includes a 50 main frame A and a supplemental frame or mask B, the latter being removably attached to the former in the well known manner. The main frame A includes side walls 5, 5 which support the usual typewriter carriage C having the usual platen 6 mounted thereon. The walls 5, 5 are

connected at a point in advance of the carriage C by a front wall 7, and located directly above said front wall 7 is a front plate 8 which forms a part of the mask B of the frame.

A plurality of type actions are located within the frame and include type bars 9 which are arranged side by side between said front plate 8 and the platen 6. The type bars 9 are pivoted on an arcuate rod 10 carried by a segment 11. A plurality of key levers 12 which are respectively 10 associated with the type bars 9, are pivoted to swing about a transverse rod 13 supported by the side walls 5 of the main frame A and operate in upwardly extending slots 14 formed in the front wall 7. Operating connections are provided between each type bar 9 and the associated key lever 12 for swinging the type bar upwardly and rearwardly to contact the platen 6 upon depression of the key lever. These sets of operating connections include a plurality of front links 15 which are pivotally mounted upon a pivot rod 16 supported by the front wall 7 above the key levers 12 and are respectively connected to the heel extensions of the type bars 9 by links 17. The key levers 12 are respectively provided with upstanding arms 18 having pin and slot connections 19 with the associated front links 15, whereby upon depression of a key lever the associated front link 15 will be swung downwardly and through the medium of the link 17 the associated type bar 9 will be swung upwardly and rearwardly to printing position. A series of coil springs 20 of equal strength have their lower ends connected to the front links 15 and function to yieldably retain said front links against downward swinging movement and also function to yieldably retain the associated key levers 12 at the upper ends of the slots 14 and against a stop 21 which is mounted on the front wall 7.

The upper ends of these springs 20 are connected to a vertically adjustable anchor plate 22 which is disposed directly in rear of the front plate 8 of the frame and extends transversely of and is common to all of said front links 15. The anchor plate 22 is provided at its ends with rearwardly and downwardly inclined lever arms 23, 23 which 45 are fulcrumed on pivot screws 24, 24 attached to the side walls 5, 5 of the main frame A. The ends of the lever arms 23 extend rearwardly beyond the pivots 24 to form short arms 25, 25, and counterbalancing springs 26, 26 are connected at their upper ends to said short arms 25, 25 and at their lower ends to the side walls 5, 5 of the main frame.

It will be observed that by moving the anchor plate 22 downwardly towards the front links, the 50

tensions of the springs 20 will be simultaneously and uniformly reduced, whereas by moving the anchor plate upwardly away from the front links, the tensions of the springs will be simultaneously 5 and uniformly increased.

To this end, I have provided an actuator bar 21 which is positioned intermediate the front plate 8 and the anchor plate 22 for movement along a straight horizontal line. The anchor plate 22 is 10 provided with spaced inclined cam slots 28, 28, the angles of inclination being identical and the slots being located equidistant from the ends of the anchor plate. The actuator 21 is provided at its ends with downwardly extending arms 29, 15 29 which terminate in rearwardly extending cam fingers 30, 30 engageable in the cam slots 28, 28. The arms 29, 29 have a sliding engagement at 29', 29' with the upper part of the front wall 7. Extending upwardly from the actuator and rigidly connected thereto is a guide 27' which is slideable 20 between the guide rail 33 and the front plate 8. Thus when the actuator 21 is moved to the right as viewed in Figure 3, the anchor plate 22 will be moved downwardly and the tensions of the 25 springs 20 will be reduced, and when the actuator is moved to the left the anchor plate will be raised and the tensions of the springs will be increased. The anchor plate actuator is thus mounted through the medium of a 3-point support consisting of the guide 27' and the arms 29-29, and by reason of this construction the actuator will 30 remain against movement in any position of its horizontal adjustment. Cooperating with the actuator 21 to retain the same in sliding contact 35 with the front plate 8 is a guide rail 33 which is secured to a flange 34 which extends rearwardly from the upper edge of said front plate 8, by screws 35.

Rigidly attached to the front edge of the actuator 21 is a combined finger-piece and indicator 40 36 and associated with the slot 32 of the front plate 8 are scale indicia with which the combined finger-piece and indicator 36 is adapted to cooperate to indicate to the operator the position of 45 the anchor plate 22 and the resultant tension of the springs 20. In Figure 2, these indicia are shown as consisting of a plurality of spaced marks 37, a minus sign 38 at the left hand end of the slot and a plus sign 39 at the right hand end of 50 said slot. In Figure 7, I have substituted the letter "L" as indicated by the reference numeral 40 and the letter "H" as indicated by the reference numeral 41 for the minus and plus signs 38 and 39 of Figure 2, signifying a high and a low tension of 55 the springs 20. In Figure 8, I have disclosed consecutive numerals 42 associated with the respective spaced marks 37, these numerals consisting of "0, 1, 2, 3, 4" and commencing at the left hand end of the slot 32.

From the foregoing, it will be observed that the anchor plate 22 may be readily adjusted either upwardly or downwardly with respect to the front links 15 by the operator who merely shifts the actuator 21 to the right or left through the medium of the combined finger-piece and indicator 36, and that by reason of the latter being located 65 at the front of the machine, the springs 20 may be readily adjusted whenever the operator desires to effect a change in the spring tension of the type actions.

I claim:—

1. In a typewriting or like machine, the combination with type bar actions arranged side by side, each action including a pivoted type bar, a key lever, and operating connections between the 75

bar and the lever, of an anchor plate located above said connections, coil springs respectively connected to said operating connections and to the anchor plate, and a single means cooperating with the anchor plate on opposite sides of the center thereof for bodily adjusting the anchor plate towards and from the operating connections to vary simultaneously and uniformly the tensions of said springs. 5

2. In a typewriting or like machine, the combination with type bar actions arranged side by side, each action including a pivoted type bar, a key lever, and operating connections between the bar and the lever, of an anchor plate extending transversely above and common to all of said 10 operating connections, said anchor plate being mounted to swing upwardly and downwardly relative to said operating connections, coil springs respectively connected to said operating connections and to the anchor plate, and a single means 15 cooperating with the anchor plate on opposite sides of the center thereof for bodily adjusting the anchor plate towards and from the operating connections to vary simultaneously and uniformly the tensions of said springs. 25

3. In a typewriting or like machine, the combination with type bar actions arranged side by side, each action including a pivoted type bar, a key lever, and operating connections between the bar and the lever, of an anchor plate located 30 above said connections, coil springs respectively connected to said operating connections and to the anchor plate, and a single manually operable means having cam connections with the anchor plate on opposite sides of the center there- 35 of for bodily adjusting the latter towards and from the operating connections to vary simultaneously and uniformly the tensions of said springs.

4. In a typewriting or like machine, the combination with type bar actions arranged side by 40 side, each action including a pivoted type bar, a key lever, and operating connections between the bar and the lever, of an anchor plate located above said connections, coil springs respectively connected to said operating connections and to 45 the anchor plate, said anchor plate being provided with an upwardly inclined cam slot, and a manually operable actuator movable in a straight horizontal line and engageable with said cam slot for bodily adjusting the anchor plate towards and 50 from the operating connections to vary simultaneously and uniformly the tensions of said springs.

5. In a typewriting or like machine, the combination with type bar actions arranged side by 55 side, each action including a pivoted type bar, a key lever, and operating connections between the bar and the lever, of an anchor plate located above said connections, coil springs respectively connected to said operating connections and to 60 the anchor plate, said anchor plate being provided with horizontally spaced upwardly inclined cam slots, and a manually operable actuator bar movable in a straight horizontal line and having cam fingers engageable in said cam slots for bodily 65 adjusting the anchor plate towards and from the operating connections to vary simultaneously and uniformly the tensions of said springs.

6. In a typewriting or like machine, the combination with type bar actions arranged side by 70 side, each action including a pivoted type bar, a key lever, and operating connections between the bar and the lever, of an anchor plate extending transversely above and common to all of said operating connections, said anchor plate being 75

- mounted to swing upwardly and downwardly relative to said operating connections, coil springs respectively connected to said operating connections and to the anchor plate, a counterbalancing 5 spring connected to the anchor plate, and means for bodily adjusting the anchor plate towards and from the operating connections to vary simultaneously and uniformly the tensions of said springs.
- 10 7. In a typewriting or like machine, the combination with type bar actions arranged side by side, each action including a pivoted type bar, a key lever, and operating connections between the bar and the lever, of an anchor plate located above said connections, coil springs respectively connected to said operating connections and to the anchor plate, said anchor plate being provided with horizontally spaced upwardly inclined cam slots, counterbalancing springs respectively connected to the end portions of the anchor plate, and a manually operable actuator bar movable in a straight horizontal line and having cam fingers engageable in said cam slots for bodily adjusting the anchor plate towards and from the operating connections to vary simultaneously and uniformly the tensions of said springs.
- 15 8. In a typewriting or like machine, the combination with a frame including a front plate, of a carriage mounted on the frame and including a platen, a plurality of type actions located within the frame and including type bars arranged side by side between the front plate and the platen, key levers, and operating connections between the key levers and the type bars, an anchor plate supported on the frame above the operating connections for movements toward and from said connections, coil springs respectively connected to the anchor plate and to said operating connections, and a single manually shiftable means mounted on the front plate and cooperating with the anchor plate on opposite sides of the center thereof for bodily moving the latter towards and from said operating connections to vary simultaneously and uniformly the tensions of said springs.
- 20 9. In a typewriting or like machine, the combination with a frame including a front plate, of a carriage mounted on the frame and including a platen, a plurality of type actions located within the frame and including type bars arranged side by side between the front plate and the platen, key levers, and operating connections between the key levers and the type bars, an anchor plate supported on the frame above the operating connections for movements toward and from said connections, said anchor plate being provided with an inclined cam slot, coil springs respectively connected to the anchor plate and to said operating connections, a manually operable actuator mounted in rear of the front plate for movements in a straight horizontal line and engageable with said cam slot for bodily adjusting the anchor plate towards and from said operating connections to vary simultaneously and uniformly the tensions of said springs, and a finger-piece attached to the actuator and operable from the exterior of the frame.
- 25 10. In a typewriting or like machine, the combination with a frame including a front plate having a horizontally extending slot, of a carriage mounted on the frame and including a platen, a plurality of type actions located within the frame and including type bars arranged side by side between the front plate and the platen,
- 30 key levers, and operating connections between the key levers and the type bars, an anchor plate supported on the frame above the operating connections for movements toward and from said connections, said anchor plate being provided with horizontally spaced upwardly inclined cam slots respectively located on opposite sides of the horizontal slot in the front plate, a manually operable actuator located in rear of the front plate and movable in a straight horizontal line 10 and having cam fingers engageable in said cam slots for bodily adjusting the anchor plate toward and from the operating connections to vary simultaneously and uniformly the tensions of said springs, a forwardly extending guide pin rigidly 15 secured to the actuator and movable along the horizontal slot in the front plate, and a finger-piece rigidly connected to said guide pin and disposed in front of said front plate.
- 35 11. In a typewriting or like machine, the combination with a frame including a front plate, of a carriage mounted on the frame and including a platen, a plurality of type actions located within the frame and including type bars arranged side by side between the front plate and the platen, key levers, and operating connections between the key levers and the type bars, an anchor plate located in rear of the front plate and extending transversely above and common to all of said operating connections, said anchor plate 30 being pivotally mounted on the frame to swing upwardly and downwardly relative to said operating connections, coil springs respectively connected to said operating connections and to the anchor plate, and manually shiftable means 35 mounted on the front plate and cooperating with the anchor plate for bodily moving the latter towards and from said operating connections to vary simultaneously and uniformly the tensions of said springs. 40
- 40 12. In a typewriting or like machine, the combination with a frame including a front plate, of a carriage mounted on the frame and including a platen, a plurality of type actions located within the frame and including type bars arranged side by side between the front plate and the platen, key levers, and operating connections between the key levers and the type bars, an anchor plate located in rear of the front plate and extending transversely above and common to all 45 of said operating connections, said anchor plate being pivotally mounted on the frame to swing upwardly and downwardly relative to said operating connections, coil springs respectively connected to said operating connections and to the anchor plate, counterbalancing springs respectively connected to the end portions of the anchor plate and to the frame, and manually shiftable means mounted on the front plate and cooperating with the anchor plate for bodily moving the latter towards and from said operating connections to vary simultaneously and uniformly the tensions of said springs. 50
- 45 13. In a typewriting or like machine, the combination with type bar actions arranged side by side, each action including a pivoted type bar, a key lever, and operating connections between the bar and the lever including a front link, of an anchor plate extending transversely above and 55 common to all of said front links, coil springs respectively connected to the front links and to the anchor plate, and a single means cooperating with the anchor plate on opposite sides of the center thereof for bodily adjusting the an- 60
- 50
- 55
- 60
- 65
- 70
- 75

- chor plate towards and from the front links to vary simultaneously and uniformly the tensions of said springs.
14. In a typewriting or like machine, the combination of a frame including a front plate having a slot, of scale indicia located on the front face of the front plate and cooperatively positioned relative to the slot, a carriage mounted on the frame and including a platen, a plurality of type actions located within the frame and including type bars arranged side by side between the front plate and the platen, key levers and operating connections between the key levers and the type bars, an anchor plate supported on the frame in rear of said front plate and above the operating connections for movements toward and from said connections, coil springs respectively connected to the anchor plate and to said operating connections, and a combined finger-piece and indicator operatively connected to the anchor plate and projecting forwardly through the slot in the front plate for bodily moving said anchor plate towards and from said operating connections to vary simultaneously and uniformly the tensions of said springs and to cooperate with said scale indicia to indicate the amount of tension of said springs.
15. In a typewriting or like machine, the combination with a frame, of a carriage mounted on the frame and including a platen, a plurality of type actions located within the frame and including type bars arranged side by side, key levers, and operating connections between the key levers and the type bars, an anchor plate supported on the frame above the operating connections for movements toward and from said connections, said anchor plate being provided with an inclined cam slot, coil springs respectively connected to the anchor plate and to said operating connections, a manually operable actuator mounted above the key levers and in front of the platen for movements in a straight horizontal line and engageable with said cam slot for bodily adjusting the anchor plate towards and from said operating connections to vary simultaneously and uniformly the tensions of said springs, and a finger-piece attached to the actuator and operable from the exterior of the frame.

ANTHONY UTZ.
